(57) **CLAIM**

The ornamental design for a display screen or portion thereof with graphical user interface, as shown and described.

DESCRIPTION

The Sole FIGURE is a front view of a display screen or portion thereof with graphical user interface.

The outermost broken line shows a display screen or portion thereof, and forms no part of the claimed design. The other broken lines show portions of the graphical user interface that form no part of the claimed design.

1 Claim, 1 Drawing Sheet
